Patented July 8, 1975

235,738

TRAY FOR PACKAGING TELESCOPIC GUN SIGHT OR THE LIKE

Danny F. Flaherty and Donald R. Payton, El Paso, Tex.,
assignors to W. R. Weaver Company, El Paso, Tex.

Filed May 22, 1973, Ser. No. 362,993

Term of patent 14 years

Int. Cl. D9—03

U.S. Cl. D9—240

FIG-1

FIG-2

FIG-3

FIG-4

FIG. 1 is a perspective view of a tray for packaging telescopic gun sight or the like showing our new design;

FIG. 2 is a top plan view thereof;

FIG. 3 is a front elevational view thereof; and,

FIG. 4 is an end elevational view thereof.

We claim:

The ornamental design for a tray for packaging telescopic gun sight or the like, as shown and described.
